UNITED STATES PATENT OFFICE.

THOMAS LLOYD, OF BOSTON, MASSACHUSETTS.

DESIGN FOR A HOLY-WATER FONT.

49,392.

Specification for Design.

Patented July 18, 1916.

Application filed May 2, 1916. Serial No. 95,004. Term of patent 14 years.

To all whom it may concern:

Be it known that I, THOMAS LLOYD, a citizen of the United States, residing at Boston, in the county of Suffolk and State of Massachusetts, have invented a new, original, and ornamental Design for Holy-Water Fonts, of which the following is a specification, reference being had to the accompanying drawing, forming part thereof.

I claim:

A design for holy water font, as shown.
THOMAS LLOYD.
